Patented May 30, 1922.

UNITED STATES PATENT OFFICE.

EDWARD LOUIS KLINGEL, OF ST. PAUL, MINNESOTA.

TELEGRAPH APPARATUS.

1,418,000.

Specification of Letters Patent. Patented May 30, 1922.

Application filed February 6, 1918. Serial No. 215,689.

To all whom it may concern:

Be it known that I, EDWARD LOUIS KLINGEL, a citizen of the United States, residing at St. Paul, in the county of Ramsey and 5 State of Minnesota, have invented a new and useful Improvement in Telegraph Apparatus, of which the following is a specification.

This invention relates to telegraph apparatus. In the operation of what is commonly called closed circuit telegraph systems now in general use, all of the relays and sounders connected with a working line, are maintained in an energized condition, 10 except when signals are being transmitted and then they are de-energized intermittently between the code signals. In ordinary practice, the closed circuit interval, that is when the telegraph instrument is energized 15 is greatly in excess of the open circuit interval, that is when the instrument is de-energized. This results in great waste of energy, but in the case of the main line circuit, this waste is not serious since the line and 20 all the relays in the line circuit are supplied with electric current with one or a number of main batteries or generators usually at the extreme ends of the line. In ordinary 25 practice, each station in the line has a sounder associated with the line relay, this sounder being part of a circuit which is entirely local to the station, therefore must be supplied with energy locally. By the use of 30 a contact on the relay armature, connections 35 are so arranged that when the line circuit is closed, the sounder circuit is closed and vice versa when the line circuit is open, the sounder circuit is open. Under usual operating conditions, the sounder circuit is generally 40 in a closed or energized condition, the greater part of the time as previously set forth, and this necessitates the use of what is commonly termed a closed circuit type of battery. In small stations, it has generally 45 been the practice to use a plurality of gravity battery cells for each local or sounder circuit. In addition to being expensive in first cost, this type of battery is exceedingly inconvenient and expensive to maintain. 50 Were it not for the fact that the sounders are kept in an energized state most of the time, dry cells or other forms of open circuit battery could be used to operate the sounder, thereby decreasing the expense and eliminating 55 the inconvenience incident to the maintenance of gravity batteries. Dry cells used

on the heretofore circuit arrangement soon become exhausted and are therefore impractical. My invention therefore deals with a method and apparatus to keep the sounder 60 circuit open or de-energized during the rest periods or when signals are not being transmitted over the line, thus permitting the use of so-called open circuit battery. My 65 method and apparatus deals specifically with the local or sounder circuit, and do not in any way change the present method of sending or receiving code signals.

The primary function of my invention is to automatically arrange the local circuit in 70 an operating condition when code signals are being transmitted over the line and to immediately and automatically disconnect the local circuit when the line is not being used to transmit signals. This is accomplished entirely without the volition of the operator.

In the accompanying drawing forming 75 part of this specification the figure is a dia-grammatic view of a circuit equipped with my improved apparatus.

In the accompanying drawing A indicates 80 a portion of a main line circuit, which leads into a station where it is connected in series with the winding 2 of a line relay B and with the usual telegraph key C, the normal 85 condition of said circuit being closed as indicated by the key. Associated with the line relay B is the usual armature 3, which is held closed against the tension of the spring 4 upon the line relay contact 5 by the mag- 90 netic energy developed by the line relay magnet. The armature 3 is connected by the conductor 6 with one side of the local battery D or other suitable source of electric current. The other side of said battery is 95 connected by the conductors 7 and 8 respec- 100 tively with the winding 9 and the armature 10 of a slow acting relay E. The opposite end of the winding 9 from that which is connected with the battery D is connected by a conductor 11 with a back contact 12, which is arranged on the line relay B, so that when the coil 2 is de-energized, the spring 4 will move the armature 3 from connection with the contact 5 and into connection with the 105 contact 12 to complete a circuit through the battery D and coil 9 of the slow acting relay E. The armature 10 is arranged when depressed by energizing the coil 9 to close a contact 13 on the slow acting relay, which 110 completes a circuit through the battery D, armature 10, conductor 14 winding 15 of

the sounder F, conductor 16, contact 5, armature 3 and conductor 6 back to battery. By means of a copper or other suitable metal cylinder 17 slipped over a portion of the 5 core 18 of the magnet of the relay E, the contact 13 is arranged to close quickly when the line relay B is energized and to keep said contact closed for a short interval, (about one second more or less) after the 10 energizing current is disconnected. This slow acting relay may be located in a sub-base of the usual sounder F or may be constructed as a separate and distinct instrument located at a distance from the sounder 15 as desired. By referring to the diagram shown in the drawing, it is apparent that as long as the contact 5 is held closed no current is being taken from the battery D. When the main line circuit A is opened, the 20 contact 5 is opened and the back contact 12 closed. The closing of the back contact 12 causes the slow acting relay E to immediately close contact 13 of the sounder circuit. During the transmission of signals over the 25 line, contact 12 is closed except during the interval when a dot or dash is being made. As the contact 12 controls the current passing to the slow acting relay E it would seem that the latter would be released when a dot 30 or dash is made, but the slow acting feature or reluctance of the relay E permits it to hold its energy during a dot or dash. Thus the contact 13 is held continuously closed as long as a series of impulses is being sent 35 over the line circuit. By the use of my invention the local battery D is only in action during the actual transmission of messages over the main line and the use of an open circuit battery is therefore made practical. 40 As a result the expense of operating the telegraph line is reduced to a minimum and the battery power in the sounder circuit conserved, which is a distinct step forward in the art to which this invention relates. It 45 is obvious that as many stations may be included in the main line A as desired, and that my improvements may be applied to the ordinary main lines of telegraph circuits now in use with little expense, the apparatus 50 employed being extremely simple and effective.

In accordance with the patent statutes, I have described the principles of operation of my invention, together with the apparatus 55 which I now consider to represent the best embodiment thereof, but I desire to have it understood that the construction shown is only illustrative, and that the invention can be carried out by other means and applied to

uses other than those above set forth within 60 the scope of the following claims:

Having described my invention what I claim as new and desire to protect by Letters Patent is:—

1. In signaling apparatus, a line circuit 65 containing a line relay and key, said line having a contact arranged to be opened when impulses are transmitted and closed during the period when impulses are not being transmitted, and a local circuit included 70 in and normally opened by said line relay when the line circuit is closed and closed when the line relay is in open position and containing a sounder and a relay having a magnet core, a reluctance coil encircling said 75 core and an armature acting under the influence of the magnetic lag in said core for keeping the local circuit closed only during the period when a series of impulses is being sent over the line. 80

2. In combination with a line circuit over which electrical impulses are adapted to be transmitted, said circuit containing a relay and key, a sounder circuit connected with said line relay in normally open condition, 85 and a sounder and sounder relay included in said sounder circuit, said sounder relay having a magnet core, a reluctance coil encircling said core and an armature acting under the influence of the magnetic lag in said core 90 for assisting in prolonging the sounder circuit in an operating condition when current impulses are being transmitted over said line circuit and for disconnecting the sounder circuit when the line circuit is not being used 95 to transmit current impulses. 100

3. In combination with a line circuit over which electrical impulses are adapted to be transmitted, said circuit containing a line relay having a normally closed contact and a normally open contact, a sounder circuit included in said closed contact and containing a sounder and an independent source of electrical current and a relay having a magnet core, a copper ring encircling said core, an 105 armature having a normally open contact in said sounder circuit and a winding connected with said open contact of said line relay; said parts being arranged so that the sounder circuit is maintained in an operating condition by magnetic lag in the magnet core when current impulses are being transmitted over said line circuit and automatically disconnected when the line circuit is not being used to transmit current impulses. 110 115

In testimony whereof, I have signed my name to this specification.

EDWARD LOUIS KLINGEL.
